United States Patent Office.

JOHN F. HECHTLE, OF WATERBURY, CONNECTICUT.

Letters Patent No. 98,060, dated December 21, 1869.

IMPROVEMENT IN HOLDING-DEVICES FOR LAMP-CHIMNEYS.

The Schedule referred to in these Letters Patent and making part of the same.

To all whom it may concern:

Be it known that I, JOHN F. HECHTLE, of Waterbury, in the county of New Haven, and State of Connecticut, have invented a new and useful Holding-Device for Lamp-Chimneys; and I do hereby declare that the following is a full and exact description of the same, reference being had to the accompanying drawings, and to the letters of reference marked thereon.

Figure 1 is a side view of a burner with my improved holding-device attached.

Figure 2 is a top or plan view of the same.

Figure 3 is a side view of a portion of the band, showing in dotted lines the pinion by which it is operated, or the two ends drawn together.

Figure 4 is a section, taken through line $z z$, showing the position of the pinion and the method of holding and operating the same.

Figures 5 and 6 are a side view and section of the same portion of the band, showing the arrangement of a clock-spring upon the shaft of the pinion to give it the proper tension.

Similar letters of reference, where they occur in the separate figures, indicate like parts.

My invention relates to an improved device for holding a lamp-chimney in its place upon the burner, and prevent it from being accidentally detached therefrom when the lamp is being carried about.

My invention consists in a band of metal, passed around the lower portion of the chimney, and held at its proper height thereon by standards placed upon the burner.

One end of this band is provided with a small gear or pinion, and the other end with a rack, corresponding, and by turning the pinion the band may be adjusted about the chimney, as close as is necessary, to firmly hold the same. It will also allow for any variation in the size of the chimney.

To enable others skilled in the art to make and use my improvement, I will proceed to describe the construction and operation of the same, with reference to the accompanying drawings.

A represents the burner of the lamp, which is of any convenient form or style.

B B B are standards, attached to the base of the burner, and extend upward upon the chimney, for a given distance, sufficient to securely hold the said chimney.

A short distance below the upper extremity of these standards, and passing freely through an aperture formed in them, a band, C, is placed, which extends around the chimney.

The standards above the band C are bent inward or rounded, to form a finger or spring, as shown in figs. 1 and 2, which alone touches the chimney.

I thus avoid the danger of breaking, which there might be if the whole band came in contact with it.

Upon the end of the band C a pinion, D, is held in any convenient way, and is brought in contact with a rack corresponding to it, and placed upon the other end of the band C.

The pinion D is operated through the shaft a by the wheel E.

A sleeve, b, may be placed over the shaft a , between the wheel E and the band, and the whole riveted tightly to the band, as shown in fig. 4, in order to give sufficient friction to prevent the band from easily becoming loosened.

This can also be accomplished by means of a coil of clock-spring, adjusted and arranged to be wound up when the band is loosened.

A socket or holder, d, may be placed upon the band C for the reception of a reflector.

My invention is operated as follows:

The band C is loosened sufficiently, by turning the pinion backward, to allow for the reception of the chimney. After it has been placed in position, the pinion is turned forward, drawing the two ends of the band together, and pressing the extremities of the standards B B B against the chimney, in which position they are held by the sleeve b upon the shaft a , as shown in figs. 3 and 4, or by the spring F, as shown in figs. 5 and 6.

Having thus fully described my invention,

What I claim as new and useful, and desire to secure by Letters Patent, is—

1. The band C, connected to the burner by means of spring standards B, and operated upon the chimney, substantially in the manner as described.

2. In combination with the band C, the operating-device, consisting of the racks and pinion D, operated by means of the wheel E, and held in position either by the friction-sleeve b or the spring F, when the same is applied to a lamp-burner, in the manner and for the purpose as herein described.

This specification, signed and witnessed, this 12th day of November, 1869.

JOHN F. HECHTLE.

Witnesses:

GEO. W. SMITH,
FRANK PRESCOTT.
